FURNACE TUBE

Lazenby C. Hamlink, Cleveland Heights, Ohio, assignor to The Gas Machinery Company, Cleveland, Ohio, a corporation of Ohio

Original application March 10, 1938, Serial No. 195,075. Divided and this application March 16, 1940, Serial No. 324,397

12 Claims. (Cl. 138—38)

The invention relates to furnaces and particularly to annealing and other heat-treating furnaces. The objects of the invention are to provide apparatus of this character which can be economically made and assembled, which is efficient in operation, and the heating elements of which will be extremely resistant to deterioration during operation. A primary object of the invention is to provide new and improved heating elements for annealing and other heat-treating furnaces, and new and improved assemblies of such heating elements and the other necessary elements of such furnaces, including an improved form of core-buster incorporated with the heating elements for the purpose of baffling the passage of the heating gases through the elements. The subject matter of the instant application has been divided out of my pending application Serial No. 195,075, filed March 10, 1938, Patent No. 2,219,894.

The annexed drawing and the following description set forth in detail certain means illustrating my improved furnace structures, such means constituting only one of the various forms in which the principles of the improved furnace structures may be embodied.

In said annexed drawing:

Figure 1 is a vertical section of a box type of integrally-formed furnace illustrating my improvements, such furnace having incorporated therein as a part thereof a type of improved refractory heating element which provides for heat treatment of the work at the two sides of the furnace, these heating elements being provided with an improved form of core-busters which act as baffles to the passage of the heating gases in order more efficiently to utilize the heat thereof;

Figure 2 is a fragmentary axial section, upon an enlarged scale, of one of the heating elements shown in Figure 1, the section being taken in the planes indicated by the line 2—2, Figures 3 and 4;

Figure 3 is a transverse section, taken in the planes indicated by the line 3—3, Figure 2; and

Figure 4 is a face view, taken from the planes indicated by the line 4—4, Figure 2, of one of the core-busters mounted in the heating elements shown in Figures 1 and 2.

Referring to the annexed drawing, I therein disclose a box type of integrally-formed furnace in which improved heating elements in the form of tubes of refractory material are incorporated for side heating of the work, these heating elements being provided with an improved form of

core-busters whereby the passage of the heating gases is baffled.

The furnace shown in the drawing has a refractory wall 1, a refractory base 2, and an arched brick roof 3 topped by insulating refractory material 4. Certain exterior strengthening structure 5 of the furnace is indicated, such as the metal casing 5, and the vertical box girders 6 connected by the top rods 7. The furnace body structure provides an interior chamber 8 within which the work may be heat-treated.

The heating elements are comprised of a plurality of aligned refractory tube sections 9 arranged interiorly adjacent the furnace wall 1. These heating elements are shown in the accompanying drawing as vertically arranged and are fired from the bottom by burners 10 and the products of combustion are discharged through upper flues 11. Lower openings 12 and upper openings 13 are formed in the furnace wall 1, through which openings, respectively, the burners 10 fire and the flues 11 receive the products of combustion. The heating elements are supported and maintained in position by tubular bottom elbow blocks 14 and tubular top elbow blocks 15, which are mounted in and project inwardly of the furnace wall 1, and which, respectively, communicate with the wall openings 12 and the bottom of the heating elements, and the wall openings 13 and the top of the heating elements. The lower elbow blocks 14 are mounted upon the base 2 and have curved passageways for the passage of the heating gases from the lower wall openings 12 to the bottom of the heating elements, and the upper elbow blocks 15 are disposed adjacently below the edge of the brick arch 3 and have curved passageways for the passage of products of combustion from the top of the heating elements to the top wall openings 13. The upper elbow blocks 15 are formed with shouldered recesses 15' and the lower elbow blocks 14 with the shouldered recesses 14' within which the upper and lower ends, respectively, of the heating elements are seated.

To baffle the heating gases passing through the heating elements, and thus assure adequate transfer of the heat from the gases to the heating elements, I provide core-busters within the heating elements, each core-buster being formed in a plurality of units 16, and special units 20, the upper face of each core-buster unit being formed with a seat 17 within which a bottom conical nose portion 18 of the adjacently upper core-buster unit is seated. In the illustrative form of construction shown in the accompanying

drawing, the core-buster units 16; as also special core-buster units 20, hereinafter fully described, are formed of refractory material.

The shape of the core-buster units is clearly shown in Figures 3 and 4. It will be noted that the central portion of the core-buster unit is a solid body, and that it is formed with lengthwise exterior downwardly-flaring spaced slots 19 through which the heating gases pass. Occasional core-buster units, such as those designated 20 in the drawing, are formed with supporting annular flanges 21 which conform to the cross-sectional shape and size of the wall of the tube sections 9 and have tongue and groove connections with the top and bottom walls, respectively, of the adjacently lower and upper tube sections 9. In Figure 1, each third core-buster unit is shown as thus formed with such a supporting annular flange 21 to form a special core-buster unit 20. It is evident that by this construction the whole series of core-buster units is supported in the heating element and that, in addition to forming supporting members, the core-buster flanges 21 also form integral parts of the heating element wall.

What I claim is:

1. A heating element for a heat-treatment furnace consisting of a plurality of tube units, and a heat-movement-baffling member disposed in said units and having flanged portions thereof forming bonds between adjacent tube units.

2. A heating element for a heat-treatment furnace consisting of a plurality of tube units, and a heat-movement-baffling member disposed in said units and having flanged portions thereof 35 interposed between the adjacent ends of contiguous units to support the baffling member.

3. A heating element for a heat-treatment furnace consisting of a plurality of tube units, and a heat-movement-baffling member disposed 40 in said units and having flanged portions thereof forming integral parts of the heating element wall.

4. A heating element for a heat-treatment furnace consisting of a plurality of tube units, and a heat-movement-baffling member comprised 45 of a series of superimposed units arranged lengthwise in the tube units and having flanged portions interposed between the adjacent ends of contiguous tube units and forming bonds between adjacent tube units and serving to support the baffling member.

5. A heating element for a heat-treatment furnace consisting of a plurality of tube units, and a heat-movement-baffling member comprised 50 of a series of superimposed units arranged lengthwise in the tube units, some of the baffling units having flanged portions interposed between

the adjacent ends of some of the contiguous tube units and forming bonds between such contiguous tube units, said flanged portions also serving as a support for the baffling member and as integral parts of the heating element wall.

6. A heating element for a heat-treatment furnace consisting of an aligned series of tube units of refractory material forming a heat conduit, at least some of which units have heat-movement-baffling portions extended into the conduit.

7. A heating element for a heat-treatment furnace consisting of a plurality of communicating tube units, and a series of superimposed apertured core-busters disposed in said units, some of said core-busters being bonded in the element wall and forming supports for the series of core-busters.

8. A heating element for a heat-treatment furnace consisting of a plurality of tube units, and a series of superimposed apertured core-busters disposed in said units, some of said core-busters having peripheral flanges conforming to the cross-sectional shape and size of the wall of the units and forming bonds between the adjacent ends of contiguous units.

9. A heating element for a heat-treatment furnace consisting of a plurality of communicating tube units of refractory material, and a series of connected heat-movement-baffling members of refractory material disposed in said units, some of said members being formed with flanges bonded in the element wall and forming supports for the series of members.

10. A heating element for a heat-treatment furnace consisting of a series of tube units interspersed with comparatively shallow bonding units between adjacent tube units, all of said units forming a continuous heat conduit, said bonding units being formed with core-busters extended into the conduit.

11. A heating element for a heat-treatment furnace consisting of a series of tube units interspersed with comparatively shallow bonding units 45 between adjacent tube units, all of said units forming a continuous heat conduit, said bonding units being formed with a series of apertured core-busters extended into the conduit.

12. A heating element unit for a heat-treatment furnace consisting of an elongated central core portion having spaced apertures therethrough and forming a heat-movement-baffling member, said core being integrally formed with an outwardly-extended annular continuous peripheral portion serving as a part of the heating element wall and also as a support for the unit.
